UNITED STATES PATENT OFFICE.

J. TYLER RYAN, OF HAMILTON, OHIO, ASSIGNOR OF ONE-HALF TO LOUIS SNIDER'S SONS, OF SAME PLACE.

ART OF MAKING PAPER OF IMPERFECTIONS.

SPECIFICATION forming part of Letters Patent No. 283,026, dated August 14, 1883.

Application filed July 2, 1883. (No specimens.)

To all whom it may concern:

Be it known that I, J. TYLER RYAN, of Hamilton, Butler county, Ohio, have invented certain new and useful Improvements in the Art 5 of Making Paper of Imperfections, of which the following is a specification.

The term "imperfections" is applied by paper-makers to scrap-paper used as paper-making stock.

10 My invention relates to an improvement in the method of applying the hot alkaline solution used in cleaning the ink from the surfaces of imperfections.

15 My invention consists in showering a hot alkaline solution upon a loose moving mass or stream of the imperfections. By this method the surfaces of the imperfections become well wetted with the solution in an instant of time. If a dry mass of imperfections be immersed in 20 a vat of the solution, many scraps of paper will unite and cling to each other like the leaves of a book, and the solution can only reach the united surfaces by the slow process of absorption, requiring much time and also requiring solution enough to soak the entire 25 body of the paper, when, in fact, only the surface may need cleansing. The same effects result from flooding a dry mass of the imperfections with the solution.

In executing my improvement I arrange the 30 blow-pipe of the cooking-tub to discharge a shower of the cleansing solution upon the imperfections as they enter the tub in a loose stream. This wets the surfaces of the imperfections in a superior and expeditious manner, 35 after which the cooking may be proceeded with as usual, or otherwise.

I claim as my invention—

The improvement in the art of making paper of imperfections, which consists in subjecting the imperfections in a loose dry stream to 40 the action of a shower of cleansing solution before cooking.
